(57) **CLAIM**

The ornamental design for a latch with a lock, as shown and described.

DESCRIPTION

FIG. 1 is a perspective front view of an oval latch with a lock showing my new design:

FIG. 2 is a rear view thereof;

FIG. 3 is a bottom plan view of FIG. 5;

FIG. 4 is a left side elevational view of FIG. 5;

FIG. 5 is a front elevational view thereof;

FIG. 6 is a right side elevational view of FIG. 5; and,

FIG. 7 is a top plan view of FIG. 5.

The back of the latch with a lock is illustrated in broken lines for illustrative purposes only and forms no part of the claimed design.
